[57] CLAIM

The ornamental design for a face plate for lighting control, as shown and described.

DESCRIPTION

FIG. 1 is a front elevational view of a face plate for lighting control showing our new design;

FIG. 2 is a right end elevational view thereof, the left end being a mirror image;

FIG. 3 is a top plan view thereof.

FIG. 4 is a bottom plan view thereof.

FIG. 5 is a rear elevational view thereof.
